UNITED STATES PATENT OFFICE

108,020

DESIGN FOR A PACKER JAR

Fred J. Petty, Muncie, Ind., assignor to Ball Brothers Company, Muncie, Ind., a corporation of Indiana

Application November 30, 1937, Serial No. 73,277

Term of patent 7 years

To all whom it may concern:

Be it known that I, Fred J. Petty, a citizen of the United States and residing at Muncie,
in the county of Delaware and State of Indiana, U. S. A., have invented a new, original, and ornamental Design for a Packer Jar, of which the following is a specification, reference being had to the accompanying drawing, forming a part thereof, wherein:

Figure 1 is a view in side elevation of a packer
jar embodying my new design;

Fig. 2 is a view in end elevation of the jar shown in Fig. 1; and

Fig. 3 is a top plan view of the jar.

I claim:

The ornamental design for a packer jar substantially as shown.

FRED J. PETTY.
